CLAIM

The ornamental design for an illuminated spinning globe and fan, as shown and described.

DESCRIPTION

FIG. 1 is a front view of an illuminated spinning globe and fan;

FIG. 2 is a left side view thereof;

FIG. 3 is a right side view thereof;

FIG. 4 is a rear view thereof;

FIG. 5 is a top view thereof; and,

FIG. 6 is a bottom thereof.

The broken dot-dash line in FIG. 6 defines the bounds of the claim and forms no part thereof.
